UNITED STATES PATENT OFFICE.

FREDERICK H. AULD AND OTTO S. MARCKWORTH, OF COLUMBUS, OHIO.

INLAID WORK.

Application filed March 2, 1928. Serial No. 258,534.

This invention relates to the art of inlaying wood veneers in the tracery of designs formed in relief and by depressions in metal plates.

5 Heretofore it has been our practice, to use in connection with such designs formed by traceries in relief and by depressions, imperforate sheets of celluloid, partially or superficially dissolved in some suitable solution, as alcohols for instance; in such cases the celluloid has performed the function of causing the veneer of wood to adhere permanently to the metal base, as well as the further function of a lamina in the composite structure. This practice has resulted in a very valuable and attractive inlaid work, which has been marketed largely and for many uses.

But in the case of designs whose tracery is such that there are very small depressed areas or spaces between the closely positioned lines of tracery of the design, it has been found that it was difficult, if possible at all, to force the veneer down into intimate and permanent contact with the surfaces of these small recesses or areas, due to imprisoned air and to the heat, employed in connection with the presses used to force the wood into the recesses, acting on the solvents used to partially dissolve the celluloid, in a manner to drive the solvents or small quantities thereof out of the celluloid in the form of vapors and/or gases which would gather between the celluloid and the surfaces of the small recesses and act as a cushion which operated to prevent the intimate or complete contact of the celluloid with the surfaces of the fine depressions.

Our problem has been to find some efficient and practical means by which this difficulty would be eliminated and pursuant to the solution of which problem there would be as complete and perfect a fitting of the celluloid with the fine or small recesses as in the case of the larger recesses where the difficulty does not seem to have been so pronounced. We have discovered and put into practice that by perforating these sheets of celluloid and using these perforated sheets in the place of the former imperforate sheets we have accomplished this. We have been able in practice to completely and satisfactorily depress by the press operation the celluloid, and, therefore, the wood itself which follows the celluloid, in the partially

dissolved state of the latter, down into the small recesses fully and completely without resistance from the air, exuded quantities of the solvent or the gaseous like product of the solvents, which exudations, whether liquid or gaseous, find their escape through the perforations in the celluloid and thence are eliminated through the pores of the wood.

We, therefore, wish to be understood as making a broad claim to a perforated celluloid sheet, partially dissolved so as to give a surface having adhesive qualities as well as to form a lamina in the composite product, which we believe we are the first to discover and apply.

In the accompanying drawings:

Figure 1 represents a sheet of celluloid with its many perforations.

Figure 2 is a like sheet of imperforate celluloid.

Figure 3 represents a veneer of wood to be used with the perforated sheet.

Figure 4 is a like sheet of veneer heretofore used with an imperforate sheet of celluloid.

Figure 5 is a sectional view of a sheet of celluloid.

Figure 6 is a similar view of a sheet of imperforate celluloid.

Figure 7 is a sectional view of a metal plate showing designs thereon in elevation or relief and depressions between the tracery thus formed, and which design is magnified in Figure 7 in order to make plain that which in practice is exceedingly small as indicated in Figure 11.

Figure 8 is a like view to Figure 7 heretofore used with the imperforate sheet.

Figure 9 is a sectional view through the metal base and its design, the celluloid sheet and the veneer showing the intimate fitting of the celluloid and, therefore, of the wood down in the recesses of the metal.

Figure 10 is a like view in which the imperforate sheet of celluloid is used and in which are shown the spaces left between the recesses and the celluloid and, therefore, the wood due to the solvents or gases referred to.

Figure 11 is a face view of the completed product made in accordance with the present invention in which the perforated partially dissolved celluloid sheet is employed as shown in Figure 9, and from which Figure 11 the character of the tracery and resulting small depressed spaces are shown.

Referring to the drawings it will be noted that Figures 1, 3, 5, 7 and 9 on the left side show the new material and the manner of its use, while Figures 2, 4, 6, 8 and 10 show the old material and the manner of its use heretofore with the resulting unfilled spaces between the celluloid and wood and the depressions or recesses.

We have made these drawings in this fashion for purposes of making plain the difference between the old and the new—old in comparison with the advent of the new perforated sheet and its manner of use.

The numeral 1 indicates a sheet of celluloid, such as commercially known, which we have perforated with many hundreds of fine holes through which may pass any solvent or any gases arising from heat as applied to the solvent, so that such exudations may escape from between the celluloid sheet and the surfaces of the depressions in the design, as before mentioned.

This sheet in practice, besides being perforated, is subjected to a dipping in, or other application thereto of, any appropriate solvent, such as alcohols or essential oils or camphor for the purpose of partially dissolving the celluloid, to the extent of a thin film. This leaves what might be termed the core of the sheet intact to form a lamina in the product and at the same time provides a surface in the nature of an adhesive which forms a strong and permanent binder between the wood and the metal, and which, because of the undissolved core of the celluloid sheet, being flexible and bendable, will permit even a bending of the completed composite article for use where it is desired to have the inlay design not only flat but in some cases bent into curvatures.

The numeral 2 indicates a sheet of wood veneer, which for purposes of illustration we have shown thicker than actually used, the thickness in practice usually being about .036 of an inch. We usually subject such sheets to a bath or application of a softening medium, such as glycerine and gelatin to make the veneer readily enter the recesses, particularly the small ones, that border the tracery of the design formed in the metal base.

The numeral 3 designates such a design plate, the lower surface being flat and the upper wrought or fashioned into such design as may be desired in which the tracery is elevated and the parts between the tracery depressed. The designs are wrought on the metal base by any of the known methods such as by engraving, or etching or by die work.

When the sheet of celluloid has been perforated and then later partially dissolved by the solvent and when the wood veneer has been treated as above stated, they then are placed together one upon the other, the celluloid resting on the portions of the design

which stand in relief and the veneer resting on the celluloid. These laminae are then treated to heat and pressure, as by a press with a flat face and a flat face platen, either or both being made hollow for the reception of a heating medium such as steam. We usually employ a pressure of from 300 pounds to 1,000 pounds per inch, according to the nature of the design and the character of the wood, whether a hard or a soft wood; and we usually employ heat ranging from 212° F. to 250° F. These operations are for the purpose of pressing the laminae into intimate relation so that the veneer and the partially dissolved perforated celluloid sheet are pressed strongly together, whereby they work down into the recesses both large and small. It is here that the function of the perforations in the celluloid is realized and performed.

In addition to expulsion of air the heat and pressure have the effect of causing a sort of exudation of the solvent, either in liquid or vaporous form. If these exudations gather, as they have heretofore when imperforate sheets of celluloid have been used by us, in the smaller recesses between the metal base and the celluloid, they become locked as it were against escape and will result in forming pockets or unfilled spaces as shown in Figure 10 where the imperforate celluloid sheet is under treatment. But in the case of the perforated celluloid sheet, as will be seen from Figure 9, the exudations instead of gathering as in the other case down in the recesses beneath the celluloid, pass through the perforations and into the veneer and are eliminated through the pores of the wood. This permits of the perfect and intimate fitting of the celluloid and the veneer upon it down into the recesses and against the walls thereof whether they be small or otherwise.

Thus our invention results in a more perfect, a more lasting and a more beneficial union of the three elements or laminae of the composite article—metal base with a design in relief, celluloid sheet in a partially dissolved state and wood veneer, such celluloid being perforated.

And this union becomes so effective and lasting that, as we found, changes in weather, in humidity, in temperature and otherwise, and even the bending of the composite product have no effect tending to separate the laminae or to allow or cause the celluloid to dislodge itself from the small recesses in the design.

We will now describe the successive steps of treatment of the materials shown at the left hand in the drawing. We do not mean to convey the idea that the practice as represented by the right hand Figures 2, 4, 6, 8 and 10 was not practical or successful because that is not the fact, but we do wish

to be understood that we have by the present invention materially and highly improved the ultimate product as well as the facility of the manipulation and union of the components or laminæ by reason of this change in the character and condition of the celluloid sheets as brought about by the perforations. The steps of this present method are:

- 10 Fabricating on a base plate a design in relief with depressions bordering the tracery of the design; perforating a sheet of celluloid; partially dissolving the surfaces of said sheet by a suitable solvent; applying such sheet upon the face of the design; applying a wood veneer upon the perforated celluloid sheet; subjecting the now composite structure to pressure and heat; and in thereby utilizing the perforations in the celluloid sheet for the passage from the depressions of any air or exudations resulting from the solvent used on the sheet and caused to flow by the pressure and heat applied when these laminæ have been superposed, where-
20 by the exudations will be driven from the depressions through the perforations and eliminated through the pores of the wood of the veneer, with the result that the celluloid in the wood is made to fully fill the depre-
25 sions in the design.

The temperature employed during the operation of pressing the parts together and the degree of pressure applied are set forth above in this specification and need not be
35 repeated here.

Finally we call attention to a sample of the completed product, made according to the present invention, as shown in Figure 11. Observe the fine lines of the design and
40 observe particularly the small spaces and depressions between the lines of tracery—observe how many of these small spaces there are in this design which is typical of thousands of other designs in which the
45 wood veneer is being inlaid in accordance with this invention.

Thus it will be understood how important and valuable the improvement here described is in practice. And it will further
50 be observed that the invention here set forth comprises both article and method of production, the element of novelty in the article being the partially dissolved perforated sheet and the consequent intimate and per-
55 manent union and fitting of the celluloid and the wood down in the recesses of the design, particularly the small recesses; and the novelty in the method resulting from the perforations in the celluloid being the intimate
60 fitting and retention of the celluloid and wood down in the smallest recesses. As a result of this, the expulsion of air and sol-
vents, (whether in a liquid or gaseous state) has been accomplished. The failure to do
65 this heretofore has frequently prevented

such intimate contact and thus left pockets between metal and the celluloid and wood above the metal.

Accordingly in our claims we are seeking to protect both the product and the method. 70

We desire to comprehend within our invention such modifications as may be clearly embraced within our claims and the scope of our invention.

Having thus fully described our invention, 75 what we claim as new and desire to secure by Letters Patent, is:

1. In inlaid work, the combination with a plate bearing a design in relief, of a sheet of celluloid perforated and partially dissolved on its surfaces, and a wood veneer, the celluloid sheet and the wood occupying the recesses adjoining the tracery of the design. 80

2. In inlaid work, the combination with a plate fashioned with a design in relief leaving depressions about the tracery, of a sheet of celluloid perforated and partially dissolved on its surfaces and a wood veneer, the celluloid and the wood occupying said de-
pressions, the celluloid acting as a binder 90 and constituting a lamina and its perforations acting to permit the passage from the depressions through the celluloid and into and through the wood of any exudations, liq-
uid or gaseous, whether air, liquid solvent or 95 vapors formed by the application of heat.

3. In inlaid work a lamina consisting of a sheet of celluloid perforated with numer-
ous holes, for the purpose set forth.

4. In inlaid work, a lamina consisting of 100 a sheet of celluloid partially dissolved on its surfaces and perforated with numerous holes.

5. In inlaid work, a lamina consisting of 105 a sheet of celluloid partially dissolved on its surfaces and perforated with numerous holes, the partial dissolution forming an ad-
hesive and the perforations forming pas-
sages for any exudations of air, or liquids
or gases resulting from the solvent used in 110 partially dissolving the celluloid so that
when said lamina is impressed into depre-
sions in a design surface such exudations
may be discharged from the depressions
through the perforations to permit the cel-
luloid to seat intimately against the walls
of the depressions. 115

6. The herein described method of mak-
ing inlaid work, consisting in fabricating a
design in relief on a base plate, in perfor-
ating a sheet of celluloid; in partially dissolv-
ing the surfaces of said sheet; in applying
the sheet over the design; and applying
wood veneer upon the celluloid sheet; and
in subjecting the now composite structure to
pressure and heat to force the wood and cel-
luloid into the depressions of the design and
to act on the celluloid to cause it to bind the
wood and metal together. 120

7. The herein described method of mak- 125

130

ing inlaid work, consisting in fabricating on an ornamental plate a design in relief with depressions bordering the tracery of the design; in perforating a sheet of celluloid; in 5 partially dissolving the surfaces of said sheet by a suitable solvent; in applying such sheet upon the face of the design; in applying a wood veneer upon the celluloid; in subjecting the now composite structure to 10 pressure and heat; and in thereby utilizing the perforations for the passage from the depressions of any exudations of air or of

liquid or vapors resulting from the solvent used on the sheet and caused to flow from the pressure and heat, the exudations passing into and through the pores of the veneer and being eliminated, whereby the celluloid and the wood are made to fill fully the depressions in the design. ¹⁵

In testimony whereof we affix our signatures. ²⁰
